PENCIL SHARPENER

Robert B. Fleming, Van Nuys, Calif., assignor to
Rudolph J. Wittek, Van Nuys, Calif.

Application June 10, 1952, Serial No. 292,655

3 Claims. (Cl. 120—89)

My invention relates generally to pencil sharpeners 15 and more particularly to a sharpener adapted for providing a sharp conical point on the graphitic cylinder of a pencil, or alternatively providing a chisel point thereon.

A primary object of the invention is to provide a single device which can be used for alternatively sharpening the graphitic cylinder of a pencil to a configuration as stated immediately above, whereby draftsmen and others can quickly acquire the desired character of point dictated by the type of lining to be done. It is for this reason that the present invention has been and is properly referred to as two-way sharpener.

An ancillary object of this invention is to provide a sharpener which can be adjusted by shifting the opposing weights to different angular relationships and with different spacings, the body member of the device having shoulders which hold the lower edges of the blades in place while the upper edges of the blades are held by simple clamping means after adjustment to suit the needs of the user.

Another object of this invention is to provide a sharpener having a vent extending along the body member adjacent to the line of convergence of the blades, so that the graphitic material shaved from the pencils can escape to prevent clogging of the sharpener.

Still another object of this invention is to provide an improved pattern of serrations on the blades, the serrations converging toward a plane extending transversely of the blades, so that these serrations are more nearly parallel to the longitudinal axis of the pencil when being sharpened, it having been found in practice that the average user of this device tends to rock the pencil in a slight arc rather than move the same in a strictly horizontal direction.

Another object, ancillary to the immediately preceding object, is to provide a pattern of serrations which is very efficient in promoting immediate escape of the graphitic shavings, since these shavings tend to be driven toward the center of the escape vent.

Finally, it is an object of this invention to provide a device of this character which is extremely inexpensive and practicable to manufacture, simple, safe and convenient to use, and which will give generally efficient and durable service.

With these objects definitely in view, this invention resides in certain novel features of construction, combination and arrangement of elements and portions as will be hereinafter described in detail in the specification, particularly pointed out in the claims, and illustrated in the accompanying drawing, in which:

Fig. 1 is a top plan view of the assembled device;

Fig. 2 is a fragmentary vertical sectional view, taken substantially on the line 2—2 in Fig. 1, the figure being on a slightly enlarged scale, and the handle being fragmentarily shown; and

Fig. 3 is a vertical transverse sectional view taken substantially on the line 3—3 in Fig. 2.

2

Similar characters of reference designate similar or identical elements and portions throughout the specification and throughout the different figures in the drawing.

Referring now to the drawing in detail the illustrated embodiment of my invention includes a body member 10 having an integral handle portion 12. The body member and handle may be constructed of wood, plastic or any other suitable material, and the particular configuration of the body member and handle is immaterial. Ordinarily, however, the body member will be an elongated flat element with a slot 14 extending longitudinally thereof. This slot 14 will have converging sides 16 and will be in communication with a vent 18, which may be considered a continuation of the slot 14, and the slot may be considered as extending completely through the body member 10. The ends of the vent 18 are preferably rounded as indicated at 20 in Fig. 2, to prevent accumulation of shavings therein, and a pair of file blades, generally indicated at 22, are mounted in the slot 14, with their lower edges resting upon shoulders 24 at the ends of the vent 18. The lower edges of the blades are identified by the numeral 26, and the upper edge portions of these same blades is identified by the numeral 28, these upper edge portions being engaged by clamping washers 30 which are screwed down tightly upon the ends of said upper edge portions 28, by means of screws 32.

It is important to note that the blades 22 can be held in a variety of positions within the slot 14, Fig. 3 illustrating the positioning of the blades 22 wherein these blades are supported entirely by said shoulders 24 and clamping washers 30. In other words, the blades can be spaced from the inclined sides 16 of the slot 14, to give the desired spacing and desired angular relationship of the blades to achieve the desired point configuration.

It will be noted that the blades 22 converge at their lower edges 26 but do not contact each other, so that a space is left therebetween for escape of graphite shavings to the vent 18. The serrations 34, 34 on each of the abrading surfaces of the blades 22 also converge toward a plane which is normal to the longitudinal axes of the blades. This configuration of the serrations is provided in view of the fact that the average user of this device tends to rock the pencil in a slight arc rather than in a true horizontal direction, and the serrations are thus made to be substantially parallel to the longitudinal axis of the pencil during the sharpening operation. The convergence of the serrations also aids in elimination of the graphitic shavings and tends to prevent clogging of the device.

The operation of this invention will be clearly understood from a consideration of the foregoing description of the mechanical details thereof, taken in connection with the drawing and the above recited objects. In recapitulation, however, it may be added that the user of the device may readily choose the type of point he desires, and merely rock the pencil longitudinally of the slot 14 without rotating the pencil when he desires a chisel point, or simultaneously rotating the pencil as the rocking motion is continued to achieve a true conical sharp point.

In view of the comparative simplicity of this invention, it is believed that further description is unnecessary. Minor variation from the illustrated embodiment of this invention may be resorted to without departure from the spirit and scope of the appended claims which properly define this invention.

I claim:

1. A pencil sharpener comprising an elongated body member having an upper face and a lower face, a slot extending longitudinally of the body member and extending from the upper face thereof deeply into said body member, said body member having end portions whereby both

3

ends of said slot are closed, opposed seats within said slot and adjacent each end of the slot, a pair of similar blades within said slot extending longitudinally thereof and seated on said seats, said blades having abrading surfaces on their adjacent sides, said blades downwardly converging transversely of the body member with the lower edges of the blades slightly spaced apart, a pair of clamping washers on the upper face of said member and having portions extending partially over each end of said slot, elongated threaded elements securing said washers to said end portions of the body member, said portions of the washers engaging the upper end portions of the blades for adjustably holding said blades in position.

2. A pencil sharpener comprising an elongated body member having an upper face and a lower face, a slot 15 extending longitudinally of the body member and extending from the upper face thereof deeply into said body member, said body member having end portions whereby both ends of said slot are closed, opposed seats within said slot and adjacent each end of the slot, a pair of similar blades within said slot extending longitudinally thereof and seated on said seats, said blades having abrading surfaces on their adjacent sides, said blades downwardly converging transversely of the body member with the lower edges of the blades slightly spaced apart, a pair of clamping washers on the upper face of said member and having portions extending partially over each end of said slot, elongated threaded elements securing said washers to said end portions of the body member, said portions of the washers engaging the upper end portions of the blades for adjustably holding said blades in position, said body member having an opening in its lower surface communicating with said slot and comprising a vent for shavings, said opening extending longitudinally of the body member between said seats, said abrading surfaces having serrations inclined slightly to the vertical and converging toward the center of said opening and toward a common vertical central transverse plane, so that when an operator rocks his pencil slightly 25 during sharpening the serrations are substantially parallel to the pencil point being sharpened.

3. A pencil sharpener comprising an elongated body member having an upper face and a lower face, a slot

4

extending longitudinally of the body member and extending from the upper face thereof deeply into said body member, said body member having end portions whereby both ends of said slot are closed, opposed seats within said slot and adjacent each end of the slot, a pair of similar blades within said slot extending longitudinally thereof and seated on said seats, said blades having abrading surfaces on their adjacent sides, said blades downwardly converging transversely of the body member with the lower edges of the blades slightly spaced apart, a pair of clamping washers on the upper face of said member and having portions extending partially over each end of said slot, elongated threaded elements securing said washers to said end portions of the body member, said portions of the washers engaging the upper end portions of the blades for adjustably holding said blades in position, said body member having an opening in its lower surface communicating with said slot and comprising a vent for shavings, said opening extending longitudinally of the body member between said seats, said abrading surfaces having serrations inclined slightly to the vertical and converging toward the center of said opening and toward a common vertical central transverse plane, so that when an operator rocks his pencil slightly during sharpening the serrations are substantially parallel to the pencil point being sharpened.
